UNITED STATES PATENT OFFICE.

J MONROE ALEXANDER, OF SPANISH FORK, UTAH.

SHOE-STAPLING MACHINE.

Application filed February 17, 1928. Serial No. 255,043.

This invention has reference to shoe making machinery, and more particularly to a machine designed for securing the soles of shoes to their uppers, by the stapling method.

5 An important object of the invention is to provide a machine of this character wherein the staple forming and setting operations will be carried out in sequence, it being only necessary for the operator to hold the shoe 10 under operation in position on the movable shoe support of the machine, while the machine is in operation.

Another important object of the invention is to provide means for adjusting the wire 15 feeding mechanism of the machine so that various lengths of wire may be cut in the formation of staples of various lengths, to the end that the machine may be used in stapling soles of various thicknesses.

20 Another object of the invention is to provide a machine wherein the staple wire feeding disk will be rotated by a step by step movement to distribute the wear directed to the milled edge of the feeding disk, throughout 25 the entire circumference thereof.

A still further object of the invention is to provide a machine of this character which will be strong and durable, efficient in operation, and one wherein the construction of 30 the machine is greatly simplified by the reduction of the number of parts necessary in the construction of the machine, thereby reducing the cost of manufacture to the minimum.

35 With the foregoing and other objects in view which will appear as the description proceeds, the invention resides in the combination and arrangement of parts and in the details of construction herein described 40 and claimed, it being understood that changes in the precise embodiment of the invention herein disclosed, may be made within the scope of what is claimed, without departing from the spirit of the invention.

45 Referring to the drawings:

Figure 1 is a side elevational view of a machine constructed in accordance with the invention.

Figure 2 is a front elevational view there- 50 of.

Figure 3 is a sectional view taken on line 3-3 of Figure 2.

Figure 4 is a sectional view taken on line 4-4 of Figure 3.

55 Figure 5 is a sectional view taken on line 5-5 of Figure 3.

Figure 6 is a sectional view taken on line 6-6 of Figure 3.

Figure 7 is a sectional view taken on line 7-7 of Figure 6. 60

Figure 8 is a sectional view through the former, showing the former in its elevated position.

Figure 9 is a sectional view through the former, showing the former in the act of 65 forming the staple.

Figure 10 is a fragmental plan view illustrating the movable anvil.

Figure 11 is a bottom plan view of the former. 70

Figure 12 is an elevational view illustrating the adjustable staple wire feeding member.

Figure 13 is a sectional view taken on line 13-13 of Figure 12. 75

Figure 14 is a fragmental enlarged sectional view of the feeding disk and cooperating feeding elements.

Figure 15 is a fragmental elevational view illustrating the means for adjusting the 80 movements of the sole engaging feeder.

Figure 16 is a sectional view taken on line 16-16 of Figure 2.

Referring to the drawings in detail, the device includes an upright body portion indicated generally by the reference character 5, the same being provided with supporting feet 6 supplied with openings whereby the machine may be firmly secured to the surface on which it is supported. 85

The body portion or frame embodies parallel spaced members 7 that are substantially wide at their upper ends, and held in spaced relation with each other by means of the spacing bar 8. 90

At the upper end of the frame is a horizontally disposed bearing 9 in which the main or operating shaft of the machine, indicated by the reference character 10, operates. Mounted on the rear end of the shaft 10, and secured thereto to move with the shaft, is a disk 11 against which the power pulley 12 is designed to move, the disk 11 being provided with a leather clutch facing 13 so that when the pulley 12 is moved toward the disk 11, the pulley 12 will be clutched to the shaft 10 to operate the shaft 10. 100

The clutching result between the pulley 12 and disk 13 is accomplished through the medium of the vertically movable rod 14 that has its lower end connected to the arm 15 which in turn is pivotally connected to 110

the base of the machine, at 16, the forward end of the arm 15 being supplied with a pedal 17.

At the upper end of the rod 14 is a yoke 18 that straddles the main shaft 10 and has pivotal connection with the arms 19 that in turn have pivotal connection with the clutch collar 20 that has its outer surface free to contact with the ring 21 loosely mounted on the shaft 10. Springs 22 connect with the arms 19 at their lower ends, and have their opposite ends anchored to the base of the bearing 9, as at 23, so that under normal conditions the clutch collar 20 is held in its inactive position, and the main pulley 12 is running free on the shaft 10. It is obvious that when the pedal 17 is forced downwardly against the tension of the spring 24 which is connected with the arm 15, the clutch collar 20 is moved laterally to clutch the power pulley to the shaft 10 in a manner as described.

Connected with the arm 15 at a point in spaced relation with the rod 14, is a rod 25 that has its upper end extending through the arm 26 of a lever pivotally mounted on the standard 5 where it is supplied with a nut 27 against which the coiled spring 28 contacts, the lower end of the spring 28 resting on the upper edge of the arm 26 so that downward movement of the arm 15 to operate the clutch, will simultaneously move the rod 25 downwardly to rock the arm 26, for purposes to be hereinafter more fully described.

The side members 7 of the frame of the machine define guides for the vertically movable block 29 that has lateral extensions 30 rubbing the forward edges of the members 7. This block is connected with an arm 31, which together with the arm 26 forms the lever mentioned above, through the medium of the links 32, so that as the rod 25 is moved, the block 29 is likewise moved vertically.

A rectangular opening extends vertically through the block 29 and accommodates the support 33 formed with a central bore for the reception of the stem 34 in which the shoe support 35 is mounted, the shoe support having a substantially square shank 36 fitted in a squared opening of the stem 34. Mounted on the shank 36 is a coiled spring 37 that is disposed between the base of the support 35 and the upper end of the stem 34 so that the support 35 may move vertically under the tension of the spring 37 during the operation of the machine.

The upper portion of the frame of the machine is cut away as at 38 providing a clearance for the wheel 39 having a cam groove 40 in its rear face and a cam groove 41 in its forward face, it being understood that the wheel 39 is secured to the shaft 10 to move therewith. Secured to the outer extremity of the shaft 10 is a cam 42 formed

with a cut away portion to permit the hammer shaft which is indicated by the reference character 43, to drop or move downwardly during the setting of the staple, this action being caused by the roller 44 extending laterally from the hammer shaft 43 and which operates over the cam 42, dropping over one edge of the cam when the wide side of the cam is at the upper side of the circle of rotation of the cam.

The hammer shaft is provided with grooves 45 formed in its side edges, which grooves accommodate the ribs 46 of the bars 47 that are secured to the forward face of the upper supporting portion 48 of the frame, so that the hammer shaft will have a true vertical movement to accomplish its purpose.

The upper extremity of the hammer shaft is reduced as at 49 and extends through the plate 50, the upper extremity of the reduced portion 49 being threaded to accommodate the adjusting nut 51 which acts as a stop to restrict downward movement of the hammer shaft, and it will be seen that when the hammer shaft snaps downwardly under the action of the coiled springs 52, the nut 51 will engage the washer 53 formed of suitable material to cushion the blow of the hammer shaft 43.

As shown, the springs 52 connect with the plate 50 and have their upper ends connected with the cross piece 54 that moves vertically with the hammer shaft in guides formed by the extensions 55 of the upper supporting portion of the frame. Secured to the cross piece 54 and extending laterally therefrom is a finger 56 against which the upper reduced end of the hammer shaft engages, so that as the hammer shaft moves upwardly the cross piece 54 moves with it and places the springs 52 under tension.

Secured at one side of the frame are bearings 57 in which the shaft 58 is secured, the shaft 58 acting as a support for the arms 59 and 60 respectively, the arm 60 carrying a laterally extending pin 61 that moves in the cam groove 41. This pin 61 is of a length to engage the arm 62 of the former 63 which is provided with an opening 64 through which the lower extremity of the hammer shaft extends.

As clearly shown by Figure 3, the lower extremity of the hammer shaft is bifurcated as at 65 so that it will move over the hollow member 66 through which the steel rod 67 moves, the steel rod being secured within the hammer shaft by means of the set screw 68.

A table indicated at 69 is supported at a point adjacent to the upper end of the machine and provides a support for the various elements cooperating with the former and cutter to be hereinafter more fully described.

As shown, the former has its lower edge cut away to fit over the former block 70, the former block being provided with a groove through which the extension 71 of the laterally movable anvil 72, extends to receive the length of wire of which the staple is to be formed. A forming opening 73 is formed in the former head and is designed to provide a clearance so that as the former head moves downwardly over the extension 71 and over the wire which has been moved to a position thereover, the staple will be formed and forced through the bore 74 of the staple guide 75. Forming a part of the staple guiding means, is an extension 76 on the former block 70 against which the forward end of the anvil 72 engages to the end that a retainer is provided so that when the anvil is returned to its normal position, the staple will be guided downwardly between the extension 76 and the end of the anvil 72.

As shown by Figure 3, the former is provided with an extension 77 extending rearwardly therefrom, and to which the depending arm 78 is secured, the arm 78 being provided with a cam surface 79 that moves against the roller 80 at one end of the movable anvil 72, to move the anvil forwardly, as the former is moved upwardly.

Disposed at the forward end of the anvil is a roller 81 that lies in the path of downward movement of the cam surface formed on the inner edge of the finger 82 so that when the former moves downwardly to a position to contact with the wire and anvil to bend the wire into a staple, the anvil is moved rearwardly or to a position as shown by Figure 3, releasing the staple to allow it to be forced through the guide 75 by the hammer or setter hammer which in the present showing is in the form of the steel rod 67. Due to the fact that the anvil is supported under the plate 83 which is mounted on the table of the machine, it will be seen that the anvil will reciprocate freely under the action of these cam surfaces.

Supported directly under the table is a bearing 84 in which the shaft 85 is mounted, the rear end of the shaft carrying a ratchet wheel 86 to be engaged by the pawl 87 carried by the arm 88 that in turn is provided with a shaft 89 operating in the adjustable block 90. The block 90 is adjusted by means of the screw 91 so that the pawl may be moved to engage alternate teeth of the ratchet wheel 86 as the arm 88 is moved, causing the shaft 85 to be rotated a greater distance than it would be if the pawl only engages successive teeth of the ratchet wheel 86.

An arm indicated at 92 supports the block 90 and has pivotal connection with the arm 93 which is secured to the extension 77 of the former. As the former moves upwardly,

the arm 92 is moved correspondingly to rotate the shaft 85 through the mechanism described.

Rotary movement of the shaft 85 results in a rotary movement of the feed roller 94 that bites into the sole of the shoe under operation to cause the sole to be fed under the machine to the end that the staple will be properly positioned.

Associated with the hammer and former and arranged laterally thereof is a cutter that includes the cutter block 95 over which the wire to be formed into staples moves, the operation of the feeding mechanism to be hereinafter more fully described being such that a length of wire will be fed to the cutter and the cutter operated to cut the wire after it has passed under the former and hammer. Forming a part of the cutter is a vertically movable head 96, the same being provided with an inclined edge 97 co-operating with the inclined edge 98 of the block 95 which edges cut the wire into the desired length for forming the staple.

The movable head 96 is formed with an opening to accommodate the guide bar 99 that extends upwardly from the table, so that the head 96 will be moved in a true vertical plane to insure the proper contact of the cutting edges. Connected with the head 96 is an arm 100 that extends downwardly from the arm 101 formed with an opening to receive the guide bar 102 of the supporting structure of the frame.

The rear end of the arm 101 is reduced and extended through the bearing 103 provided with grooves in its upper and lower surfaces to fit within the bifurcated end 104 of the arm 59 so that as the arm is moved, the movable head 96 is moved vertically into and out of engagement with the block 95 to cut the wire. Movement is imparted to the arm 59, by the pin 105 extending laterally therefrom, and which operates in the cam groove 40 of the wheel 39.

It is to be understood however that when a single power shaft operates to move the hammer, former and cutter, the cams are so constructed that the various members are properly timed to accomplish their respective operations at the proper time to cut, form and set the staple.

Guide bars 99 extend upwardly from the table and are arranged in spaced relation with each other acting as a support for the movable head 96 as before stated which movable head is provided with a rear portion 107 that acts as a support for the arm 108 that in turn is supplied with a laterally extended finger 109 disposed within the space 125 between the arms 110 of the wire feeding mechanism.

While the bars 99 extend upwardly from the table, they are supported on the movable bar 111 provided with lateral ribs oper-

ating in grooves formed in the table as clearly shown by Figure 13 of the drawings. A segmental rack extends forwardly from the table and cooperates with the pawl 112 of the lever 113 which is pivotally supported under the table and which has connection with the bar 111, through the medium of the link 114 with the result that as the lever 113 is moved, the bar 111 and guide bars 99 will 10 be moved longitudinally of the table to bring the finger 109 to a position adjacent to the outer ends of the arms 110 or to a point adjacent to the inner ends of the inclined surfaces 115 thereof, for purposes to be herein- 15 after more fully described.

Supporting arms 116 have downwardly extended end portions 117 which are provided with openings to receive the bolt 118 that pivotally connects the arms to the table 20 of the machine. These arms 116 are arranged in parallel spaced relation with each other and are formed with aligning openings to receive the shaft 118' that extends an appreciable distance beyond the rear surface 25 of one of the arms 116 as clearly shown by figure 4 of the drawings. Secured to this shaft 118' is a feed wheel 119 that has its rear surface cut away adjacent to the periphery defining a recess 120 formed with notches 30 defining teeth to bite into the wire, which in the present showing is indicated by the reference character 121, to feed the wire into the machine.

Directly under the wheel 119 is a shaft 122 35 on which the rollers 123 and 124 are mounted, and between which the wheel 119 operates. Teeth 125 are formed on the inwardly extended portion or hub of the roller 123 and over which the wire moves in being fed 40 to the machine, it being understood that movement of the wheel 119 exerts a forward pull on the wire to move it into the machine.

In order that the wheel 119 may be moved 45 into close engagement with the wire operating over the teeth 125, a pivoted arm 126 is provided, the arm being connected with the table at 127, the upper extremity of the arm passing between the arms 116 from 50 where it passes through the plate 128 that connects the outer ends of the arms 116 as clearly shown by Figure 6 of the drawings.

Mounted at the upper end of the arm 126 is a lever 129 that has cam surfaces 130 at 55 its inner end, the cam surfaces being designed to contact with the washer 131 against which the upper end of the coiled spring 132 bears, the lower end of the coiled spring resting on the plate 128. Thus it 60 will be seen that as the lever 129 is moved downwardly to a position as shown by Figure 6, pressure is exerted on the upper end of the coiled spring 132 which in turn urges the arms 116 downwardly resulting in the 65 wheel 119 being placed under pressure suffi-

cient to cause the teeth thereof to bite into the wire.

As clearly shown by Figure 13, a ratchet wheel 133 is secured to the shaft 118' and is engaged by the pawl 134 carried by the yoke 135 that is provided with openings to accommodate the shaft 118'. A regulating screw indicated at 136 extends through the yoke 135 and contacts with the pawl 134 for adjusting the pawl with respect to the teeth of the ratchet wheel 133. The arms 110 have 70 pivotal connection with the yoke 135 at 137, or at their inner ends, the arms being connected adjacent to their outer ends by means of the bolt 138 which passes through openings in the arms 110, there being provided a coiled spring 139 positioned between the arms 110 and coiled around the bolt 138, to restrict movement of the arms 110 towards 80 each other.

Thus it will be seen that due to this construction the operator may by moving the lever 113 move the head and arm 108 to bring the finger 109 to a position adjacent to the outer ends of the arms 110, whereupon it will be seen that with each vertical movement of the arm 108 caused by the vertical movement of the head, the arms 110 will be rocked to operate the pawl which in turn moves the ratchet wheel to operate the 90 shaft 122 a predetermined distance, and since the finger 109 operates through a greater space than it would if the finger were moved to a position adjacent to the inner ends of the inclined surfaces 115, there will 95 be a certain amount of lost motion to the end that the arms 110 will be rocked only slightly, this being necessary in the formation of a substantially short staple. Should it be 100 desired to position a longer staple, it is obvious that by a movement of the lever 113 the head and arm 108 as well as the finger 109 carried thereby may be moved to bring the finger adjacent to the inner end of the inclined surface 115, whereupon the arms 110 will be engaged by the finger 109 throughout substantially the entire upward 105 movement of the head 96 causing a greater movement of the ratchet and ratchet wheel to rotate the shaft 122 a greater distance, 110 and consequently feeding a greater length 115 of wire to the machine.

A bracket 140 extends laterally from the frame of the machine and provides a support for the arms 141 between which the reel 142 operates, the reel being provided with laterally disposed pins 143 on which the wire, which in the present showing is indicated by the reference character 144, is wound, the wire being fed to the machine through the guide 145 that is shown as curved upwardly and supported in the pivoted support 146.

In the operation of the machine a shoe 130 to be stapled is positioned over the shoe

support 35 in a manner as shown by Figure 2, whereupon the pedal 17 is pressed downwardly by the foot of the operator which causes the clutch mechanism on the main power shaft 10 of the machine to throw the main power pulley 12 over which a belt not shown, operates, into operation.

As the shaft 10 rotates the wheel 39 is rotated and the former head is moved upwardly to a point above the forming anvil, whereupon it descends. Prior to the downward movement of the former head, it is to be understood that the anvil 92 is moved laterally until the extension 71 thereof lies in a position as shown by Figure 10 or in a position directly under the former head. The cutter now comes into play and severs a length of the wire which is held in a position directly over the extension of the anvil, whereupon the former descends to form the staple.

The construction of the cam grooves and cams of the machine is such that as soon as the staple has been formed, the hammer or setter which is indicated at 67 moves downwardly contacting with the staple to force it into the shoe.

As the operation of the machine continues these operations are repeated, it being understood that the shoe under treatment is held on the support as shown by Figure 2 and fed under the former head in the usual and well known manner.

It is believed that in view of the foregoing detail description, a further detail description of the device is unnecessary.

I claim:

1. In a shoe stapling machine, a frame, a vertically movable former operating on the frame, a hammer operating through the former, a wire cutter, a main shaft, a wheel having cam grooves in opposite side faces thereof, a mutilated cam on the outer end of the shaft, pivoted arms mounted adjacent to the wheel, laterally extending pins carried by the arms and disposed within the grooves to move the arms, means for transmitting movement of the arms to the former and wire cutter, to operate the cutter in advance of the former, and means operated by the mutilated cam for moving the hammer to set a staple formed by the former.

2. In a staple forming machine, a frame,

a former operating on the frame, a cutter movable on the frame, means for feeding a length of wire to the former, said feeding means including a shaft, a wheel mounted on one end of the shaft, a ratchet wheel on the shaft, a yoke carrying a pawl to engage the ratchet wheel, a pair of diverging arms secured to the yoke to move the yoke and pawl to move the ratchet wheel and feed wheel, an arm movable with the cutter, a pin extending laterally from the arm and disposed between the diverging arms to engage the arms to move the arms and ratchet wheel, means for adjusting the pin towards and away from the outer ends of the arms to cause the pin to engage the arms at different points to adjust the movement of the feed wheel, and means for operating the former.

3. In a shoe stapling machine, a frame, a former including a former head movable vertically with respect to the frame, said former head having an opening, a guiding member under the former head, said guiding member including an upstanding member, said guiding member having a slot adjacent to the upstanding member, an anvil having an extension adapted to move into the slot, means for feeding a length of wire to the anvil, the opening in the former head adapted to accommodate the upstanding member and extension of the anvil when the former head moves to its active position, means for retracting the anvil, and a staple setting member movable through the former head and guide to set the staple.

4. In a shoe stapling machine, a frame, a vertically movable former mounted on the frame, an anvil supported by the frame, a roller at each end of the anvil, an arm extending laterally from the former and carrying cams, said cams adapted to engage the rollers to move the anvil towards and away from the former, means for feeding a length of wire to the anvil to be engaged by the former to form a staple, and a reciprocating staple setting member adapted to engage the staple after it has been formed to set the staple.

In testimony that I claim the foregoing as my own, I have hereto affixed my signature.

J MONROE ALEXANDER.
